CLAIM

The ornamental design for an audio device wall mount, as shown and described.

DESCRIPTION

FIG. 1 is a front elevation view of an audio device wall mount;

FIG. 2 is a rear elevation view thereof;

FIG. 3 is a top plan view thereof;

FIG. 4 is a bottom plan view thereof;

FIG. 5 is a first side view thereof;

FIG. 6 is a second side view thereof;

FIG. 7 is a perspective view thereof; and,

FIG. 8 is a bottom perspective view thereof.

The dashed broken lines in the figures illustrate portions of the audio device wall mount that form no part of the claimed design.

The dot-dash broken lines illustrate boundary lines and form no part of the claimed design.

1 Claim, 8 Drawing Sheets
